DESIGN FOR A BRUSH

Nicholas Kirsten, Detroit, Mich.

Application September 8, 1936, Serial No. 64,768

Term of patent 7 years

To all whom it may concern:

Be it known that I, Nicholas Kirsten, a citizen of the United States, residing at Detroit, county of Wayne, in the State of Michigan, have invented a new, original, and ornamental Design for a Brush, of which the following is a specification, reference being made to the accompanying drawing, forming part thereof.

Fig. 1 is a top plan view of a brush showing my new design.

Fig. 2 is a side elevation thereof.

Fig. 3 is a bottom plan view thereof, the brush handle being broken away for convenience of illustration.

I claim:

The ornamental design for a brush, as shown and described.

NICHOLAS KIRSTEN.
